UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A NECK-SCARF.

SPECIFICATION forming part of Design No. 11,781, dated May 18, 1880.

Application filed January 28, 1880. Term of patent 7 years.

To all whom it may concern:

Be it known that I, THOMAS J. FLAGG, a citizen of the United States, residing at New York, in the county and State of New York, 5 have invented and produced a new and original Design for Made-Up Scarfs, of which the following is a specification, reference being had to the accompanying drawing, forming part thereof.

10 My design relates to a double-headed or reversible scarf formed with crossed aprons, whose opposite ends are so finished and connected by an intermediate piece as that either end of the complete scarf may be exposed and 15 worn as the head of the scarf.

The leading feature of my design consists in an outline for the complete scarf presenting substantially the general contour of a curved-sided shield at one end and of a heart 20 at the other, the lower ends of both shield and heart being cut off or lost by the overlapping of the two.

In the accompanying drawing, A A' are 25 the aprons of the scarf. Each apron presents in outline an extended ovoidal form having its apex cut off diagonally by a line, a a. The aprons are crossed, with their rounded ends b b placed in the same direction to form one end of the scarf, and with their opposite angular 30 ends, a a, so arranged as that the acute angle in each forms the outer angle, d, of that end of the scarf.

B B are neck-pieces interposed at each end of the scarf between the ends of its aprons. 35 The upper edge, c, of each neck-piece is slightly curved inwardly in a line which at the angu-

lar end of the scarf merges into and forms an extension or continuation of the diagonal lines a a of the apron ends.

D is the neck-band, which forms, however, 40 no part of the design.

The exterior contour of this design for a double scarf is that of a shield conjoined at its base to the base of a smaller heart, the bases of the two overlapping, so as to be cut off and 45 lost at the merging-point w, the shield, completing the head of the double scarf, being formed with an upper edge, a a c, inwardly curved from point to point, and with curved sides, and the heart, forming the opposite head of the 50 scarf, having edges b b, rounded in a semicircular form, all as clearly shown in the drawing.

I claim as my invention—

The design for a double-headed reversible 55 scarf herein shown and described, the same consisting of two aprons, both of a similar ovoidal form with their apexes cut off diagonally, and which are crossed one upon the other, so that their rounded ends shall present, in connection with the upper edge of an 60 interposed neck-piece, a heart-shaped outline at one end of the scarf, and their opposite angular ends shall present a shield-shaped outline at its opposite end, the contour of the 65 lower ends of the heart and shield respectively being merged and lost in each other by overlapping.

THOS. J. FLAGG.
